CLAIM

The ornamental design for a weather station, as shown and described.

DESCRIPTION

FIG. 1 is a front elevational view of a weather station showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a front, top and right side perspective view thereof; and,

FIG. 8 is a rear, bottom and left side perspective view thereof.

The broken lines in the drawings illustrate portions of the weather station which form no part of the claimed design. The oblique shade lines in the drawings represent a reflective surface.
